UNITED STATES PATENT OFFICE

153,269

DESIGN FOR A COMBINED RADIO, CLOCK,
AND LAMP

Irving Engel, East Orange, N. J.

Application January 5, 1948, Serial No. 143,538

Term of patent 3½ years

(Cl. D48—20)

To all whom it may concern:

Be it known that I, Irving Engel, a citizen of the United States, residing at East Orange, in the county of Essex and State of New Jersey, have invented a new, original, and ornamental Design for a Combined Radio, Clock, and Lamp, of which the following is a specification, reference being had to the accompanying drawing, forming part thereof.

The figure is a perspective view of a combined radio, clock, and lamp, showing my new design.

I claim:

The ornamental design for a combined radio, clock, and lamp, as shown.

IRVING ENGEL.
